UNITED STATES PATENT OFFICE.

NATHAN J. MEIGS, OF WEST HAVEN, CONNECTICUT, ASSIGNOR OF ONE-HALF TO ELMER L. KNOWLES, OF NEW HAVEN, CONNECTICUT.

LATCH.

SPECIFICATION forming part of Letters Patent No. 605,170, dated June 7, 1898.

Application filed July 15, 1897. Serial No. 644,596. (No model.)

To all whom it may concern:

Be it known that I, NATHAN J. MEIGS, a citizen of the United States, residing at West Haven, in the county of New Haven and State 5 of Connecticut, have invented certain new and useful Improvements in Door-Latches; and I do hereby declare the following to be a full, clear, and exact description of the invention, such as will enable others skilled in 10 the art to which it appertains to make and use the same.

The object of my invention is to provide a door-latch of simple and comparatively inexpensive construction the latch-bolt of which 15 is locked and released by endwise movement of the knob-spindle, thereby obviating any necessity of turning the latter in either opening or closing the door.

To this end my invention consists in the 20 door-latch constructed and operating as hereinafter fully set forth.

Referring to the drawings, in which like numerals designate like parts in the several views, Figure 1 is a cross-section of the 25 latch, taken at line $x-x$ of Fig. 2. Fig. 2 is a side view of the latch with the cover of the casing removed. Fig. 3 is an end view of the latch. Fig. 4 is a plan view of the latch-bolt. Fig. 5 is a cross-section of the striker-plate, 30 taken at line $y-y$ of Fig. 6. Fig. 6 is a face view of the striker-plate.

The numeral 1 designates the latch-casing, which, as herein shown, is adapted to be secured within a mortise in the door 2 in the 35 usual manner. The latch-bolt 3 has in its upper edge a recess 4, which receives a fixed stud 5 on the casing, and a spring 6, secured at one end to a second stud 7 on the casing and at its opposite end to the latch-bolt, holds 40 the latter in engagement with the stud 5 in such manner as to permit it to have both longitudinal and rocking movement upon said stud, while at the same time exerting a constant outward pressure upon the latch-bolt. 45 At its outer end said latch-bolt has its side edges beveled to a V shape, as shown in Fig. 3, and has its lower edge provided with the inclined surface 8, for a purpose which will presently appear. Near its said outer end 50 the latch-bolt is provided with the upwardly-projecting ear 9, the outer side of which is

curved, substantially as shown in Fig. 2. At its inner end the latch-bolt terminates in the projection 10 of reduced size.

The knob-spindle 12 passes transversely 55 through the casing 1, as usual, and it is provided on its lower side with a projection or lug 13, which in one extreme position of the spindle engages the rear end of the latch-bolt 3, as shown in Fig. 2, and locks the latter 60 against inward movement.

The knobs 14 15 are secured to the knob-spindle at such points as to permit sufficient endwise movement of the latter to move the lug 13 out of the path of movement of the 65 projection 10 of the latch-bolt, thus releasing said latch-bolt and permitting it to move inwardly. A lug 16 on the side of the knob-spindle serves to limit its movement within the casing in one direction. 70

The striker-plate 17 (shown in Figs. 5 and 6) has the usual hole 18 to receive the screw by which it is secured to the door-casing and is provided with the usual socket 19 to receive the end of the latch-bolt 3, the front 75 wall 20 of which socket is beveled or inclined, as shown. At its front side said plate is provided with the incline 21, extending upwardly and rearwardly from its lower edge, and the front edge of the plate above said incline is 80 beveled or inclined on its outer surface, as shown at 22.

A spring 23, surrounding the knob-spindle between the knob 14 and the side of the door, normally retains the spindle in the position 85 shown in Fig. 1 and returns it to such position after the spindle has been moved longitudinally to release the latch-bolt.

The operation of the latch thus constructed is as follows: Assuming the door to be open 90 and the latch-bolt 3 to be in the position shown by full lines in Fig. 2, if the door be moved to its closed position the inclined surface 8 on the latch-bolt is first caused to engage the incline 21 on the striker-plate, thereby raising the outer end of the latch-bolt and depressing its inner end to cause it to clear the lug 13 of the knob-spindle. The continued closing movement of the door causes the V-shaped outer end of the latch-bolt to engage 95 the beveled surface 22 at the front edge of the striker-plate and forces the latch-bolt in- 100

wardly to the position shown by broken lines in Fig. 2. When the end of the latch-bolt reaches the socket 19 of the striker-plate, its spring 6 forces it outwardly into said socket, 5 at the same time elevating its inner end and depressing its outer end, thus causing it to be positively locked in such position by lug 13 on the knob-spindle, as before described. The door is now positively locked against ac- 10 cidental opening. To open the door, it is necessary simply to pull upon the knob 15 or push on knob 14, such action in the first place moving the knob-spindle sufficiently to cause the lug 13 to clear the end of the latch-bolt, 15 and then by the engagement of the inclined side 20 of the socket 19 in the striker-plate with the outer end of the latch-bolt forcing the latter inwardly to permit the door to open freely. The curved outer edge of lip 9 on the 20 latch-bolt rides against the upper wall of the opening in the casing through which the latch-bolt projects and steadies the latter in its rocking movement. By thus enabling the door to be unlatched by an endwise movement of 25 the knob-spindle I greatly enhance the convenience with which the door can be manipulated as compared with the usual necessity of turning said spindle.

The latch herein described is of simple and 30 inexpensive construction, sure and positive in its operation, and not liable to get out of working order.

Having thus fully described my invention, what I claim, and desire to secure by Letters 35 Patent, is—

1. In a door-latch, the combination with a latch-bolt adapted for both longitudinal and a rocking movement, of a knob-spindle adapted for a limited longitudinal movement in a 40 plane at a right angle to that of the move-

ment of said latch-bolt and having means for engaging the latch-bolt at one end of its movement to lock the latter against movement, and a striker-plate having a socket to receive the outer end of said latch-bolt and inclined surfaces for causing both an upward and an inward movement of the latch-bolt as it approaches said socket, substantially as set forth. 45

2. In a door-latch, the combination with a longitudinally-movable and pivotally-supported latch-bolt and a spring for imparting outward movement thereto, of a non-revoluble knob-spindle adapted for a limited endwise movement and carrying a lug or projection which, at one extremity of its movement engages the end of said latch-bolt and locks it against inward movement, and a striker-plate having a socket to receive the end of said latch-bolt, an incline for raising the outer 60 end of the latter, and inclined surfaces for forcing the latch-bolt inwardly as it approaches and leaves said socket, substantially as set forth. 55

3. The combination with the casing 1 having stud 5, of latch-bolt 3 having the recess 4 and ear 9, spring 6, and knob-spindle 12 having the lug 13, substantially as set forth. 65

4. The combination with the latch-bolt 3 having a V-shaped outer end and provided 70 with the incline 8, of knob-spindle 12 having lug 13, spring 6, and striker-plate 17 having socket 19, incline 21, and inclined surfaces 20 and 22, substantially as set forth.

In testimony whereof I affix my signature 75 in presence of two witnesses.

NATHAN J. MEIGS.
